METHOD AND APPARATUS FOR SCANNING
SOUND-FILM CONTROL TRACKS

Charles C. Davis, West Los Angeles, Calif., assignor to Western Electric Company, Incorporated, a corporation of New York

Application September 24, 1941, Serial No. 412,072

10 Claims. (Cl. 179—100.3)

This invention relates to the scanning of a slow-acting control track recorded in the sprocket hole portion of a photographic film for any desired purpose, an example being the control of the reproduced volume of a sound record occupying a longitudinal portion of the same film.

It is found that for most sound sources the range in volume between loudest and faintest passages is greater than can be successfully recorded on the emulsions now available for the sound negative and the sound positive, the latter being commonly printed on the same film with the corresponding picture. As a result, the reproduced sound is usually compressed in volume range as compared with the original: either the higher levels are arbitrarily reduced, or the lower levels raised, or both, causing in any event a loss of dramatic effect. It has been proposed to overcome this deficiency by recording, simultaneously with the compressed sound signal, a volume control track registering the variations in gain of the recording electrical circuit. This control track, appearing on the sound positive together with the sound record itself, is relied on to cause automatically the appropriate compensatory variations in reproducing gain to the end that the sound reproduction shall be re-expanded to exhibit the true volume relations of the original sound.

The control track may be located in any longitudinal portion of the film consistent with leaving undisturbed the accepted sound and picture areas, and for reasons of operating convenience the sprocket hole portion has been commonly chosen. This choice, however, introduces the difficulty that the track is interrupted by the sprocket holes. The frequency of these interruptions is 96 per second, corresponding to the standard film speed of 90 feet per minute, and the current in a photocell scanning the sprocket hole control track contains a strong component of this frequency. The sprocket holes, besides introducing a 96-cycle component of photocell current, restrict the recordist to the use of a slow-acting control, for the reason that during the passage of the perforation through the scanning light beam no information can be transmitted to the reproducing circuit.

Whatever the type of recording adopted for the control track, whether variable density, variable area, or the so-called direct current track, the 96-cycle component must appear in the reproduction of the control track. It can, of course, be overcome by appropriate electrical means, including usually rectification and filter-

ing. However, all these appurtenances are expensive and cumbersome, and may themselves constitute a hazard to successful sound reproduction.

5 It is the object of my invention to provide an optical arrangement whereby the scanning of the interrupted control track may be rendered continuous, thereby making unnecessary the correcting networks alluded to above.

10 The apparatus I provide and method I use to effect this object will be readily understood from the detailed description of the accompanying drawing, which shows an embodiment of my invention with particular reference to a direct current control track:

Fig. 1 is a schematic view in side elevation of a sound-picture reproducer showing my apparatus in relation to the other parts of the sound reproducer mechanism;

20 Fig. 2 shows in plan a positive sound-picture film having a direct current control track in the sprocket hole portion with the sound track and picture areas located as usual. In this figure the emulsion coated surface is below the plane of the drawing; and

25 Fig. 3 is an edge view of the film showing a section thereof taken along the line 3—3 of Fig. 2 and dimensioned to show the exact relations of the sprocket holes and the elements constituting the embodiment of my invention shown in Fig. 1.

30 It will be understood that for the sake of greater clarity, the three figures have been drawn to different scales. In all figures the same reference numerals designate corresponding parts.

35 Referring to Fig. 1, the film 1 is caused by the usual driving mechanism, not shown, to pass from the feed reel and picture head above through the sound-reproducing apparatus to the take-up reel below. These reels and the picture projection apparatus are not shown since they form no part of the present invention. Leaving the continuously rotating sprocket 2 of the picture head film 1 passes, in turn, under guide roller 3, horizontally under plane mirror 4, over guide roller 5, vertically down through the sound gate 6, under the continuously rotating sprocket 7, thence over guide roller 8 to the take-up reel. Rollers 3' and 5' coact with guide rollers 3 and 5, respectively, to provide a slight drag and so insure the film's passing in the desired plane under and parallel to mirror 4.

40 The remaining structural elements of my invention, coacting with mirror 4 are light source 9, positive lens 10 which renders parallel a por-

tion of the light from source 9, and photoelectric cell 11. Photocell 11 is electrically supplied through conductors 13 and 14 from the battery 15 and polarizing resistance 16, as shown in Fig. 1. The anode and cathode of cell 11 are connected, respectively, to the control grid and the cathode of a variable-mu tube, such as the Western Electric 283A or equivalent, as indicated in Fig. 1. This variable-mu tube, not itself a part of the present invention, thus is enabled to control the amplification of the sound-reproducing electrical system in accordance with variations in current in cell 11 which current variations are themselves occasioned by variations in the light returned by mirror 4 through film 1 to fall on the cathode surface of cell 11. The conventional sound-reproducing system comprising lamp 17, optical system 18, sound gate 6 and photocell 19, together with appropriate amplifiers and loudspeakers, serves for the reproduction of sound track 20 of Fig. 2. The control of the electrical system by a variable-mu tube is well known, being fully explained in U. S. Patent 2,245,652, June 17, 1941, to J. E. Dickert, and need not be described herein. It will be understood that the sound-reproducing system of Fig. 1 is solely illustrative.

In the described embodiment of my invention, the reflecting surface of plane mirror 4 is positioned approximately parallel to the plane of travel of film 1 and at a distance therefrom approximately equal to the altitude of an equilateral triangle of sides each equal to half the pitch of the perforations in film 1. Light source 9, lens 10 and photocell 11 are positioned as shown in Figs. 1 and 3 on the opposite side of the film from mirror 4 and in such relation to each other, to film 1 and to mirror 4 that the parallel beam of light leaving lens 10 traverses film 1 and is incident on mirror 4 at an angle of approximately 30 degrees from normal incidence, being reflected from mirror 4 to fall on the photosensitive surface of cell 11 after again traversing the film. Suitable choice of the size and shape and relative longitudinal location of the film areas effectively illuminated in the two light passages insures that the control track 21 shall be scanned by the light beam from lens 10, under the condition that no light reaches cell 11 which has not been influenced by the control track record. It may be desired to house light source 9, lens 10 and photocell 11 in an enclosure such as 12 in Fig. 1, leaving as shown an appropriate aperture for exit and re-entry of the scanning light.

Source 9, lens 10, mirror 4 and cell 11 are so mounted that the optical axis of the direct and reflected beams is in a plane perpendicular to the plane of the film and intersects that plane in the longitudinally central line of the sprocket hole portion. Details of a suitable mounting are not shown, as these are matters of convenient mechanical design. Moreover, it is recognized that those skilled in the art may, if they choose, employ a different geometrical arrangement from that shown in Figs. 1 and 3 without ceasing to use the method of my invention as further defined in the paragraph immediately below.

The method of my invention requires that the film areas effectively illuminated in the two passages of the scanning beam shall be equal rectangles, the centers of which are separated lengthwise of the film a distance greater than the length of the sprocket hole interruption, that is greater than 0.078 inch, but less than the length of film between consecutive sprocket holes,

that is, less than 0.109 inch; or, alternatively, a distance selected within these limits, preferably their mean, increased by any convenient multiple of the sprocket hole pitch. It is required that 10 two opposite sides of these rectangles be at right angles to the direction of film travel and approximately equal to the sprocket hole width (0.110 inch), while the sides parallel to the direction of film travel may have any convenient length, the same for both rectangles, preferably not exceeding one-half the perforation pitch, that is, one-half of 0.187 inch. It is clear that under these conditions the entire width of the sprocket hole control track is scanned and that cell 11 receives no light which has escaped the control track.

Fig. 3 shows, similarly to Fig. 1 but to a larger scale, one form of apparatus by means of which my invention may be applied to effect continuous scanning of the direct current sprocket hole control track of Fig. 2. Here plane mirror 4 is a rectangle of dimensions 0.0935 inch parallel to the direction of film travel $\times$ 0.110 inch perpendicular thereto, the latter dimension not being shown in Fig. 3. The reflecting surface of mirror 4 is positioned parallel to the plane of the film and perpendicularly distant 0.081 inch therefrom. Since the parallel beam of light from lens 10 is incident on both film 1 and mirror 4 at an angle of 30 degrees from normal incidence, the dimensions and positioning of mirror 4 serve to constitute this mirror an optical stop: light from lens 10 illuminates the film in the reflected path over an area extending transversely the width of the sprocket holes and longitudinally one-half the perforation pitch. An equal area is effectively illuminated in the direct path, for the reason that no light traversing film 1 outside this effective area is returned by mirror 4 to reach cell 11.

In the arrangement of apparatus shown in Fig. 3 the two illuminated areas are longitudinally contiguous with centers separated lengthwise of the film by one-half the perforation pitch. The area ABA'B' of Fig. 2 is continuously illuminated and the light reaching cell 11 is wholly under the control of track 21. It is not, however, essential that the areas illuminated be longitudinally contiguous, nor that their longitudinal extent be one-half the perforation pitch, nor that their centers be spaced only as shown in Fig. 3. The method of my invention is applied and its object attained by any arrangement which insures that the light reaching the photocell shall have passed twice through the track to be scanned, provided the areas illuminated on the two passages be equal rectangles, with one pair of opposite sides approximately equal to the sprocket hole width and transverse to the direction of film travel, and with centers longitudinally separated on the film by approximately an odd multiple of one-half the perforation pitch. For example, mirror 4 may properly be located three (or five, etc.) times 0.081 inch above the plane of film 1; the centers of the areas of light passage will then be separated lengthwise of the film by three (or five, etc.) times one-half the perforation pitch. An optical stop may be introduced in any of the well-known ways to limit the longitudinal extent of the areas illuminated, if desired, until they become comparable with the conventional sound track scanning line. Moreover, an opaque mask provided with a rectangular slit of appropriate size and shape may be introduced between light source 9 and lens 10, the slit to be imaged by lens 10 on the film, illuminating thereon the

desired rectangle; in this case the image-forming light diverges after traversing the emulsion and requires reflection from a concave mirror, replacing plane mirror 4, to converge again on the film in the required rectangle of second passage. The concave mirror for this purpose is easily chosen to insure the desired spacing of the centers of the areas illuminated. Other arrangements, broadly equivalent to those I have particularly described, will suggest themselves to those skilled in the art of sound-film recording and reproduction.

It will be seen that the object of my invention is attained by the method and apparatus of the foregoing description. In Fig. 3, control track element CA' is effective to control the current in cell 11 while CA' lies athwart the direct beam from lens 10, the preceding sprocket hole leaving unobstructed the reflected beam from mirror 4, and again when CA' intercepts the reflected beam, the succeeding sprocket hole replacing CA' in the direct beam. Thus, CA' undergoes two scannings which slightly overlap (CD=EA'), the effect of sprocket hole interruption is annulled and the control track is scanned as if it were continuous. It will be recalled that a slow-acting control track is contemplated: for such a track the overlap indicated in Fig. 3 is harmless, and the centers of the two scanning areas may be separated by several sprocket holes before the interval between the two scannings becomes a large fraction of the time within which the control track calls for the completion of a change in reproducer gain.

I desire also to point out that my method may be applied to effect the continuous scanning of a control track over the sprocket holes even where this track is a frequency record, modulated in either amplitude or frequency, provided the scanning areas be reduced in longitudinal extent to be each substantially the conventional sound scanning line. However, in this case special networks are required after the photocell, and the advantage of simplicity is less to be expected.

It will be observed that I have shown in Fig. 1 the structure of my invention in a location above the sound-reproducing system. It may be desired to locate elsewhere the control track scanning system, and this may be done without departing from the spirit of my invention.

While I have described and shown my apparatus and method for scanning a sound film control track interrupted by the sprocket holes, I do not desire to be limited thereto, for it is readily seen that my invention may be adapted to permit effectively continuous scanning of an interrupted longitudinal film track of any type, provided the interruptions are periodic and the length of the interrupted portion is not greater than half that of the cycle of interruption.

What is claimed is:

1. In a sound film reproducing system, means for scanning a periodically interrupted track occupying a longitudinal portion of a sound film, comprising a light source, an optical system for directing a beam of light from said source to pass through a rectangular area of said track, one dimension of said rectangular area being transverse to said track, a mirror positioned to reflect said beam to return through said track over a rectangular area equal and similarly oriented to the area of first passage through said track, the centers of said rectangular areas being separated longitudinally of said track a distance approximately equal to an odd multiple of half the length

of a cycle of interruption, and a light sensitive device receiving said returned beam after its second passage through said track and responsive to variation of the light flux in said returned beam.

5 2. In a sound film reproducing system, means for scanning a periodically interrupted track occupying a longitudinal portion of a sound film, comprising a light source, an optical system for directing a beam of light to pass through an area of said interrupted track, a mirror positioned to reflect said beam to return through an equal area of said track, the centers of said areas being longitudinally separated by approximately half the length of a cycle of interruption, and a light sensitive device receiving said returned beam and responsive to variation of the light flux therein.

15 3. In a sound film reproducing system, means as in claim 2 for scanning a periodically interrupted track occupying a longitudinal portion of a sound film, wherein each area of light passage through said interrupted track is a rectangle of width approximately equal to that of said track and of length not greater than one-half the length along said track occupied by a complete cycle of interruption.

20 4. In a sound film reproducing system, means as in claim 2 for scanning a periodically interrupted track occupying a longitudinal portion of a sound film, wherein each area of light passage through said interrupted track is a rectangle of width approximately equal to that of said track and of length not greater than one-half the length along said track occupied by a complete cycle of interruption, and wherein the axes of the direct and reflected light beams are each incident on said track at an angle approximately 30 degrees from normal incidence.

25 5. In a sound film reproducing system, means for scanning a control track in the sprocket hole portion of a sound film, comprising a light source, an optical system for directing a beam of light from said source to pass through a rectangular area of said track, one dimension of said rectangular area being transverse to said track, a mirror positioned to reflect said beam to return through said track over a rectangular area equal and similarly oriented to the area of first passage through said track, the centers of said rectangular areas being separated longitudinally of said track a distance approximately equal to an odd multiple of half the distance between centers of consecutive sprocket holes, and a light sensitive device receiving said returned beam after its second passage through said track and responsive to variation of the light flux in said returned beam.

30 6. In a sound film reproducing system, means for scanning a control track in the sprocket hole portion of a sound film comprising a light source, an optical system for directing a beam of light to pass through an area of said sprocket hole portion of the film, a mirror positioned to reflect said beam to return through said portion of the film over an area equal to that of first passage, the centers of said areas being longitudinally separated by approximately half the sprocket hole pitch, and a light sensitive device receiving said returned beam and responsive to variation of the light flux therein.

35 7. In a sound film reproducing system, means as in claim 6 for scanning a control track in the sprocket hole portion of a sound film, wherein each area of light passage through said control track is a rectangle of width approximately equal to that of the sprocket holes and of length not greater than one-half the sprocket hole pitch.

8. In a sound film reproducing system, means as in claim 6 for scanning a control track in the sprocket hole portion of a sound film, wherein in each area of light passage through said control track is a rectangle of width approximately equal to that of the sprocket holes and of length not greater than one-half the sprocket hole pitch, and wherein the axes of the direct and reflected light beams are each incident on said volume control track at an angle approximately 30 degrees from normal incidence.

9. In a sound film reproducing system, the method of continuously scanning a periodically interrupted track occupying a longitudinal portion of a sound film which comprises directing a beam of light through said interrupted track, illuminating thereby on said track a rectangular area having one dimension transverse to said track and approximately equal to the width thereof and extending lengthwise of said track a distance no greater than the length of one-half cycle of interruption, reflecting said transmitted beam to return through an equal and similar area of said track, the centers of said areas being longitudinally separated a distance approximately

5 equal to an odd multiple of half the length of a cycle of interruption, and receiving said returned beam after its second passage through said track on a photosensitive device responsive to variation of the light flux in said returned beam.

10. In a sound film reproducing system, the method of continuously scanning a control track in the sprocket hole portion of a sound film which comprises directing a beam of light through said control track, illuminating thereby on said control track a rectangular area having one dimension transverse to said track and approximately equal to the width thereof and extending lengthwise of said track a distance no greater than one-half the sprocket hole pitch, reflecting said transmitted beam to return through an equal and similar area of said track, the centers of said areas being longitudinally separated a distance approximately equal to an odd multiple of half the sprocket hole pitch, and receiving said returned beam after its second passage through said track on a photosensitive device responsive to variation of the light flux in said returned beam.

CHARLES C. DAVIS.
